US0D1002658S

(12) **United States Design Patent** (10) **Patent No.:** **US D1,002,658 S**
Moon et al. (45) **Date of Patent:** **** Oct. 24, 2023**

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Hyeyoung Moon**, Suwon-si (KR); **Jaejo Ko**, Suwon-si (KR); **Kyoungtaek Kim**, Suwon-si (KR); **Changhwan Kim**, Suwon-si (KR); **Hyesoo Kim**, Suwon-si (KR); **Hyewon Park**, Suwon-si (KR); **Sungchan Bae**, Suwon-si (KR); **Hyeonseung Lee**, Suwon-si (KR); **Eunhae Lim**, Suwon-si (KR); **Yookyung Ham**, Suwon-si (KR)

(73) Assignee: **Samsung Electronics Co., Ltd.**, Suwon-si (KR)

(**) Term: **15 Years**

(21) Appl. No.: **29/827,290**

(22) Filed: **Feb. 18, 2022**

(57) **CLAIM**

We claim the ornamental design for a display screen or portion thereof with graphical user interface, as shown and described.

DESCRIPTION

The sole FIGURE is a front view of a display screen or portion thereof with graphical user interface showing our new design.

The outermost broken lines in the FIGURE depict a display screen or thereof and form no part of the claimed design. The remaining broken lines in portion the FIGURE depict portions of the graphical user interface which form no part of the claimed design.

1 Claim, 1 Drawing Sheet
